(57) **CLAIM**

I claim the ornamental design for a pet toy pinecone, as shown and described.

DESCRIPTION

FIG. 1 is a top view of a pet toy pinecone, showing my new design;

FIG. 2 is a bottom view thereof;

FIG. 3 is a front view thereof;

FIG. 4 is a rear view thereof;

FIG. 5 is a left side elevational view thereof;

FIG. 6 is a right side elevational view thereof; and,

FIG. 7 is a perspective view thereof.

The pet toy comprises two parts: a pinecone (left part) and a sucker (right part).

1 Claim, 3 Drawing Sheets
